THERMOSTATIC SWITCH

Filed June 8, 1948

UNITED STATES PATENT OFFICE

2,537,582

THERMOSTATIC SWITCH

John J. Grace, Brooklyn, N.Y.

Application June 8, 1948, Serial No. 31,637

1. Claim. (Cl. 200—140)

1

This invention relates to a thermostat, the thermostat constituting the subject matter of the present invention, being an improvement over the construction shown in my prior Patent No. 2,122,575 issued May 15, 1917.

The principal object of this invention is to provide a dual or twin warning control mechanism that will be responsive into a combination high and low calibration of temperature, humidity, pressure and the like from an indicator dial.

It is another object of the invention to provide a thermostat which is of such construction that it may be manually set for high and low temperatures and cause a visual or audible signal to be energized when the temperature of an oven, refrigerator, or other confined space reaches a predetermined high or low point and thus warn an attendant that the predetermined high or low temperature has been reached and that attention should be given to the apparatus with which the thermostat is associated.

Another object of the invention is to provide a thermostat wherein setting arrows or pointers constituting adjustable contacts may be moved to adjusted positions in predetermined spaced relation to opposite sides of a main arrow or pointer serving as a movable contact and thus allow a warning member to be actuated when either a predetermined high or low temperature has been reached.

Another object of the invention is to provide a thermostat or circuit closer which includes setting pointers carried by and extending radially from shafts which are rotatably mounted through a panel in concentric relation to each other and are provided with knobs by means of which the shafts may be individually turned to set the pointers.

Another object of the invention is to provide a device of this character wherein the pointers not only serve as indicators for allowing accurate setting of the thermostat but also serve as contacts which are to be engaged by the main pointer or arrow of the thermostat.

Another object of the invention is to provide a thermostat wherein the setting pointers are mounted in the forward portion of a frame rearwardly of a front panel for the frame and have portions bent to form rearwardly extending arms which are of such length that as a main pointer located back of the setting pointers moves in response to variations in temperature it will engage an arm of a setting pointer and thus close a circuit for exercising the signal member.

Another object of the invention is to provide a thermostat wherein the main pointer and its operating mechanism may be of conventional formation and the dial across which its pointer extends also serves as a dial for the setting pointers mounted in the forward portion of a frame in which the main pointer and its operating mechanism are mounted.

Another object of the invention is to provide a thermostat which is of simple construction, very easy to set, and not liable to get out of order.

With these and other objects in view the invention consists of an improved construction and arrangement of parts shown in the accompanying drawings wherein:

Fig. 1 is a front view of the improved thermostat.

Fig. 2 is a sectional view taken vertically through the same.

Fig. 3 is a sectional view upon an enlarged scale taken longitudinally through the mounting and setting means for the adjustable pointers.

Fig. 4 is a diagrammatic view showing the wiring for the improved thermostat.

This improved thermostat or circuit closer is intended for use in connection with an oven, furnace, refrigerator, incubator, or the like which is subject to temperature variations and should have the attention of an attendant when the variation in temperature reaches a predetermined extent.

The circuit closer may be mounted in any desired manner and has a frame 11 provided with front and rear panels 2 and 3 held in spaced relation to each other by sleeves 4 through which securing bolts 5 pass. The panels will thus be spaced from each other such a distance that when a thermostat 6 is mounted in the rear portion of the frame 11 it will be spaced from the front panel. This thermostat is of conventional construction and includes the usual pointer or arrow 7 carried by a rotatable shaft 8 and disposed in front of a dial 9 having the usual temperature readings upon its front face so that by observing the position of the pointer relative to the dial an accurate reading of the temperature may be obtained. An arm 10 extends from the shaft 8 out of the casing 11 of the thermostat and is connected with the expandable and contractable element 12, and from an inspection of Fig. 1 it will be seen that as the element 12 expands and contracts the shaft 8 will be rotated and the pointer 7 moved along the dial.

The front panel 2 is formed of glass, or other

transparent material, so that the dial 9 and the pointer 7 may be seen by a person standing in front of the thermostat, and through this front panel is formed an opening 14 through which a metal sleeve or bushing 15 is mounted. A tubular shaft 16 is rotatably mounted through the bushing 15 and has its forward portion 17 externally reduced in diameter and of such length that it projects forwardly from the front panel a sufficient distance to carry a knob 18 which is secured to the tubular shaft by a set screw 19. A second shaft 20 of greater length than the tubular shaft is rotatably mounted through the tubular shaft and projects forwardly from the front end of the outer tubular shaft so that a knob 21 may be mounted upon the forward portion of the inner shaft 20 and secured thereon by a set screw 22. A disk or slip ring 23 fits about the rear end portion of the inner shaft between its head 24 and the rear end of the outer shaft 16 and when the knob 21 is applied and its set screw 22 tightened the ring will be confined between the head of the inner shaft and the rear end of the outer shaft and frictionally gripped thereby.

A wire 25 connects the ring with the negative side of a battery 26, or equivalent source of electric energy, and from the positive side of this battery extends a wire 27 which is attached to one terminal of an electric bell, buzzer, light or equivalent signalling device, 28. The other terminal of the signalling device is connected with the shaft 8 by a wire 29 and when the gap between the wires 25 and 29 is closed the signal will be energized and thus give warning that a temperature variation of predetermined extent has been reached.

In order to allow closing of the gap between the wires there have been provided pointers or arrows 30 and 31 formed of conductive material and carried by the rear end of the outer shaft 17 and the head 24 of the inner shaft 20. These arrows project radially from the shafts and have mid-portions crimped to form arms 32 and 33 which project rearwardly from the pointers and are of such length that they are in the path of movement of the pointer or arrow 7. The arrows 30 and 31 are visible through the transparent front panel 2 and by grasping the knobs 18 and 21 the shafts may be individually rotated and the arrows swung about the dial 9 until they are disposed at desired markings on the dial. When so adjusted the arrows 30 and 31 will be spaced at opposite sides of the arrow 7 and as the arrow 7 moves in response to temperature changes it will eventually engage the arm 32 of the arrow 30 or the arm 33 of the arrow 31. When this occurs the circuit will be closed and the signal energized. It will be seen that the arrows 30 and 31 serve not only as setting arrows but also as adjustable contacts which are manually shiftable to positions in predetermined spaced relation to opposite sides of the arrow 7 which serves as a movable contact. As the ring 23 is gripped between the heads of the two shafts it is possible to turn the shafts as a unit after the arrows 30 and 31 have been set and thus simultaneously

move the arrows relative to the thermostat pointer 7 without changing the distance between the arrows. If so desired, an electrically operated control for a heater, refrigerator, or the like may be installed in the circuit instead of the signal and automatically opened or closed in response to temperature variations.

From the foregoing description of the construction of my improved device, the operation thereof and the method of assembly will be readily understood, and it will be seen that I have provided a comparatively simple, inexpensive and efficient means for carrying out the various objects of the invention.

While I have particularly described the elements best adapted to perform the functions set forth, it is apparent that various changes in form, proportion and in the minor details of construction may be resorted to, without departing from the spirit or sacrificing any of the principles of the invention.

Having thus described the invention, what is claimed is:

In a thermostatic signal, a frame having a transparent front panel, a thermostat in said frame spaced rearwardly from the panel and having a dial visible through the panel and a pointer of conductive material pivotally mounted in front of the dial centrally thereof and constituting a movable contact extending radially of the dial, a bushing mounted through said panel and disposed concentric with the pivotal mounting of the pointer, a tubular outer shaft rotatably mounted through said bushing and projecting forwardly therefrom and having a head about its rear end abutting the rear end of the bushing, an inner shaft rotatably mounted through the outer shaft and projecting forwardly therefrom, and having a head at its rear end, knobs fitting about the forwardly projecting portions of said shafts and disposed one in front of the other, set screws carried by said knobs and gripping the shafts and securing the knobs to the shafts for independent turning of the shafts by their knobs, a ring fitting about the inner shaft between one of the shafts and gripped by the heads and constituting means for frictionally turning one shaft with the other, and pointers of conductive material extending from the heads of said shafts radially of the dial at opposite sides of the movable contact and constituting adjustable contacts, said adjustable contacts having crimped portions forming arms extending towards the dial in position for engagement by the movable contact.
